UNITED STATES PATENT OFFICE.

WALTER C. KARNES, OF JOPLIN, MISSOURI.

TIMER.

1,847,633.

Specification of Letters Patent. Patented July 27, 1920.

Application filed October 7, 1919. Serial No. 329,057.

To all whom it may concern:

Be it known that I, WALTER C. KARNES, a citizen of the United States, residing at Joplin, in the county of Jasper, State of Missouri, have invented certain new and useful Improvements in Timers, of which the following is a specification.

My invention relates to circuit breakers and particularly to that type known as "timers" employed in the ignition systems of internal combustion engines.

It is the purpose of my present invention to provide an improved brush structure for timers which will greatly simplify the arrangement and which will materially reduce the cost of manufacturing and in addition my improved brush structure is so arranged as will permit its incorporation in the standard "Ford timer" with very little change and at a minimum of expense.

It is also the purpose of my present invention to produce a timer brush structure which will be efficient in operation and which will embody a minimum number of parts so connected together as to be proof against disarrangement no matter how hard the usage or how serious the neglect to which it is subjected.

With the above and other purposes in view my invention consists in the details of construction and in the arrangement and combination of parts to be hereinafter more fully described and particularly pointed out in the claims.

In describing my invention in detail reference will be had to the accompanying drawing wherein like characters of reference denote corresponding parts in the several views, and in which—

Figure 1 is a bottom plan view of a timer embodying my invention with the base of the timer casing removed and the timer shaft shown in section; and

Fig. 2, a perspective view of my improved brush structure.

Referring to the drawings A indicates a timer case which carries therein the usual contact supporting ring 10 formed of any desirable insulating material and having embedded therein the usual contacts 11 all of the well known construction and common to the timers employed in the ignition system of the engines of "Ford" cars.

My improved brush structure is shown as comprising a sleeve 12 which is engaged on the upper end of the timer shaft 13, the latter being driven from the cam shaft of

an associated engine as is usual. This shaft 13 carries a lateral pin 14 for a purpose that will presently appear. The sleeve 12 is provided with spaced lateral arms 15 and 16 which are connected by an abutment pin 17. This sleeve is further provided with an arm 18 which is engaged through an opening 19 in a brush element 20, said element being held against disengagement from the arm 18 by a cotter or other suitable fastening device 21 passed through said arm. The brush element is preferably constructed of spring steel and is carried around the sleeve 12 and extended between the arms 15 and 16 and between the pin 17 and the sleeve 12. The brush element is then returned upon itself to form a free contact terminal 22 as clearly shown in Fig. 2. The lower end of the sleeve 12 is provided with notches or recesses 23 which are adapted to selectively receive the pin 14 and thereby non-rotatably secure the sleeve to the shaft 13. By providing this adjustment of the sleeve 12 relatively to the shaft 13 I am enabled to advance and retard the time of the spark as will be obvious.

I claim:

1. A brush structure for timers comprising a body portion adapted to be non-rotatably secured to a timer shaft, an abutment carried by the body portion, and a brush element secured to the body portion and returned upon itself around said abutment to form a contact engaging terminal.

2. A brush structure for timers comprising a body portion adapted to be non-rotatably secured to a timer shaft, spaced lateral arms on the body portion, an abutment pin connecting the arms, and a brush element secured to the body portion and extending between the arms and around the abutment to form a contact engaging terminal.

3. A brush structure for timers comprising a body portion adapted to be non-rotatably secured to a timer shaft, an abutment carried by the body portion, an arm on said body portion, and a brush element engaged on said arm and returned upon itself around said abutment to form a contact engaging terminal.

In testimony whereof I affix my signature in the presence of two witnesses.

WALTER C. KARNES.

Witnesses:

P. R. COLEMAN,
AVIS BAGGEE.
